CLAIM

The ornamental design for a display screen with graphical user interface, as shown.

DESCRIPTION

FIG. 1 is a front view of a graphical user interface for a display screen or portion thereof showing our new design; FIG. 2 is a front view of a second embodiment thereof; and, FIG. 3 is a front view of a third embodiment thereof.

The outer broken line perimeter showing the display screen and the broken lines within showing text and elements of the graphical user interface are provided for the purpose of illustrating portions of the article and form no part of the claimed design. The sections of the graphical user interface that have shading form a part of the claimed design and the shading in the figures forms part of the claimed design as shown.
